SIGNAL APPARATUS FOR ROADWAYS

John Spake, Shelby, N. C., assignor of one-half
to A. L. Wood, Shelby, N. C.

Application January 2, 1940, Serial No. 312,169

8 Claims. (Cl. 116—67)

My invention relates to signal apparatus for roadways.

An important object of the invention is to provide apparatus of the above mentioned character which will produce an audible signal, at intervals, as the vehicle traveling upon one road approaches the intersection with another.

A further object of the invention is to provide apparatus of the above mentioned character which will operate a visual signal when the vehicle traveling on one road approaches the intersection.

A further object of the invention is to provide apparatus of the above mentioned character which will reset the signal to the normal or safety position when the vehicle is about to pass the signal.

A further object of the invention is to provide a trip device which is adapted to be installed in the roadway and which will be depressed by the wheels of the vehicle passing over the same.

A further object of the invention is to provide a trip device which is so constructed that the load of the vehicle is not supported by the movable parts of the trip device, after such movable parts are depressed.

A further object of the invention is to provide a trip device of the above mentioned character having movable parts arranged in the path of travel of the vehicle to move vertically and properly held against lateral displacement.

A further object of the invention is to provide mechanical means operated by the trip device for actuating an audible signal.

A further object of the invention is to provide mechanical means operated by the trip device to operate a remote visual signal.

A further object of the invention is to provide means to automatically compensate for the contraction or expansion of the cable due to coefficient of expansion.

Other objects and advantages of the invention will be apparent during the course of the following description.

In the accompanying drawings forming a part of this application and in which like numerals are employed to designate like parts throughout the same,

Figure 1 is a plan view of apparatus embodying my invention,

Figure 2 is a longitudinal section taken on line 2—2 of Figure 1,

Figure 3 is a transverse section taken on line 3—3 of Figure 1,

Figure 4 is a plan view showing a slight modification of the invention,

Figure 5 is a plan view of one of the trip devices,

Figure 6 is a side elevation, parts in longitudinal vertical section and parts broken away,

Figure 7 is a transverse vertical section taken on line 7—7 of Figure 6,

Figure 8 is a longitudinal vertical section taken on line 8—8 of Figure 5,

Figure 9 is a perspective view, partly diagrammatic, of a plurality of the trips and associated elements,

Figure 10 is a transverse vertical section taken on line 10—10 of Figure 8,

Figure 11 is a similar view taken on line 11—11 of Figure 8,

Figure 12 is a perspective view of a coefficient of expansion compensating device,

Figure 13 is a plan view of the trip device adjacent to the intersection,

Figure 14 is a transverse section taken on line 14—14 of Figure 13,

Figure 15 is a side elevation of the trip device shown in Figure 13, parts in vertical section and parts broken away, and,

Figure 16 is a longitudinal section taken on line 16—16 of Figure 13.

In the drawings, wherein for the purpose of illustration are shown preferred embodiments of my invention, the numeral 20 designates a main highway and 21 designates a side road, the same crossing for providing an intersection 22. Disposed upon the right side of the main highway 20, upon opposite sides of the side road 21 are trip devices 23 and 24, which are substantially identical.

The trip devices in each group are spaced suitable distances apart, such as five hundred feet, although the distance may be varied, as found advantageous. The trip devices 24 are arranged near the intersection 22 and are disposed upon opposite sides thereof, as shown.

Each trip device 23 and 24 comprises an outer casing or box 25, preferably formed of concrete. The openings are cut in the roadway, adjacent to the outer edges thereof and suitable molds are provided for the pouring of the concrete casings or boxes 25. When the casings or boxes

are poured a wooden strip 26 is anchored in the outer face of the same, at the sides and the inner end, adjacent to the top of the casing or box.

The operating mechanism of the trip is arranged within a metal casing or housing 27 which is inserted within the outer concrete casing or box and fits snugly therein. Each trip device com-

prises a pair of upper arms 28, which are arranged transversely of the roadway 20 and extend across the outer portion thereof for a suitable distance. The upper arms 28 extend longitudinally within the metal casing 27 and are pivotally mounted upon a horizontal shaft 29, held within bearings 30. The numeral 31 designates a lower arm, arranged between the upper arms 28, and pivotally supported at its inner end with respect to the roadway 20 by a transverse shaft 32, carried in bearings 33, Figures 8 and 11. The lower arm has its outer end extending beyond the outer ends of the arms 28 and this outer end is provided with an elongated slot 34, slidably receiving a stub-shaft 35, carried by the ends of the arms 28 and rigidly secured thereto. When the upper arms 28 are depressed, the stub-shaft 35 slides within the slot 34 and depresses the lower inner arm 31. The outer end of the lower arm 31 is guided in its vertical movement within a vertical slot 36, formed in a stationary plate 37. This guide means prevents the arm 31 and the arms 28 from being shifted laterally, when the wheels of the vehicle pass over the same. Arranged between the arms 28 is a spacer 38, rigidly attached to these arms by any suitable means as by bolts or the like. The outer end of the spacer 38 terminates at the point 39 so that it does not interfere with the relative movements between the arms 28 and 31. The function of the spacer is to provide a flat supporting surface for the flexible cover, to be described.

Arranged adjacent to the outer end of the casing 27 is a vertical casing or housing 40 preferably formed of metal. The housing 40 is provided with louvers 40' so that the audible signal may be readily heard. The housing 40 is of course rigidly attached to the casing 27. The numeral 41 designates a flexible cover extending over the top surfaces of the arms 28 and spacer 38. This flexible cover also extends over the casing 27 and concrete box 25 and is attached to the wooden strips 26, and is also attached to the casing 40 at 42. It is preferred to form a tight even joint at the edges of the cover 41 by means of a tar filler 41'.

Arranged within each vertical housing 40 is an audible signal device comprising a gong 43, supported by a bracket 44. This gong is arranged to be engaged by clappers 45, carried by flexible fingers 46, secured to a hub 47. This hub is rotatable upon a horizontal shaft 48, carried in bearings 49. The hub 47 is rigidly secured to a gear 50, and may be formed integral therewith. The gear 50 is arranged to be engaged by a rack 51, depending from the outer end of the arm 31 and rigidly secured thereto. It is thus seen that when the arm 31 is depressed the rack 51 will engage the gear 50 and rotate it whereby the clappers 45 will strike the gong 43 and when the arm 31 rises, the rack 51 will rotate the gear 50 in the reverse direction again causing the clappers to strike the gong. The arm 31 extends into the housing 40, as shown, and the free end of the arm is connected at 52 with a cable 53, extending upwardly, and passed about a grooved pulley 54, supported in a bracket 55, attached to the top of the housing 40. The cable 53 extends downwardly and is connected with a weight 56, operating within a vertical guide 57. The weight and associated elements serve to raise the arm 31. The upward movement of the arm 31 is limited by contact with the top of the slot 36 and by engagement with the spacer 38, while the downward movement

of the arm 31 and the arms 28 is limited by stops 58, secured to the sides of the casing 27 and arranged to contact with the lower edges of the arms 28.

A visual signal is mounted at each of the trip devices 24, at the intersection. This visual signal comprises a vertical post 59, rotatable in a bearing 60, and having an end-thrust bearing 61 at its lower end. The post 59 extends above the housing 40 for a suitable distance, and carries a signal element or semaphore 62, which is swung horizontally by the post 59. When there is no traffic on the main highway 20 approaching the side road 21, the semaphore 62 is parallel with the side road 21, but when the vehicle traveling upon the main highway 20 approaches the intersection, the trip devices 23 turn the vertical post 59 and the semaphore is swung horizontally to a position at a right angle to the side road 21. Means are provided to connect the arms 31 of the trip devices 23 with the post 59, to turn it. This means comprises a cable 63, having branches 64 extending over pulleys 65, supported by fixed shafts 66. The cable branches 64 extend downwardly and are attached to the free end of the arms 31 at 52.

At the trip device 24, arranged adjacent to the intersection 22, the cable 63 is wound about a grooved pulley 67. The winding may be for half the circumference of the grooved pulley. This grooved pulley is mounted upon a horizontal fixed shaft 68, carried by the housing 40. The grooved pulley 67 is preferably formed integral with a second grooved pulley 69 and the grooved pulley 67 is also preferably formed integral with a bevel gear 70, engaging a bevel gear 71 rigidly mounted upon the vertical post 59. It is thus seen that when the cable 63 is pulled by the downward movement of the arm 31 of either trip device 23 that this cable will turn the grooved pulley 67 and this turning movement will be transmitted to the vertical post 59, which will then turn the semaphore 62 at a right angle to the side road. The semaphore 62 will remain in this set position until returned to the normal position by the action of the arm 31 of the trip device 24. The pulley 69 has a cable 72 wound thereon in a reverse direction to the winding of the cable 63 on the pulley 67 and the cable 72 passes over a guide pulley 73, carried by a fixed shaft 74 and the cable 72 is attached to the free end of the arm 31 of the trip device 24, at 52. It is thus seen that when the arm 31 of the trip device 24 is depressed, this arm will pull upon the cable 72, causing it to rotate the pulley 69, which will turn the vertical post 59 in a reverse direction so that the semaphore 62 will again be arranged parallel with the side road.

The cable 63 will operate satisfactorily under different weather conditions and different temperatures. However, I contemplate connecting compensating devices therein, to take care of the coefficient of expansion of the cable 63. In Figure 12, I have shown one of these compensating devices. When the device shown in Figure 12 is used, the cable 63 is cut and one end of the cable is attached to a disk 74 while the cable is passed through an opening 75 in the other disk 74. The cable has frictional engagement within the openings 75, and the extent of this frictional engagement is regulated by changes in temperature. Further, the disks 74 are slidable within a cylinder 76, and the frictional contact between the disks and the cylinder is also varied by changes in temperature. While 75

I contemplate using this compensating device, my invention is not restricted to the use of the same.

In Figure 4 the main highway 20 is shown curved instead of straight, and the cables 63 extending between the trip devices pass through guide devices 21.

The operation of the apparatus is as follows:

Assuming that the semaphore 62 is set parallel to the side road 21 and that a vehicle is approaching the trip device 23 which is the most remote from the intersection, then when the vehicle reaches the first trip device 23 it will depress the arm 31 of this trip device. When the arm is depressed the cable 63 is pulled and the semaphore 62 is swung for 90° and is then arranged at a right angle to the side road 21, providing a visual signal at the intersection. When the arm 31 of the first trip device moves downwardly and then upwardly, the gong 43 is sounded upon both movements of the arm 31. When the vehicle passes over the next trip 23, the gong is sounded upon the down and up movements of the arm 31. When the vehicle passes over the trip device 24 adjacent to the intersection, the gong is again sounded and the semaphore turned for 90° so that it is again arranged parallel with the side road 21. Figure 9 shows the arms 31 of the trip devices 23 raised and the arm 31 of the trip device 24 is also raised. When the first arm 31 of the trip device 23 to the right, is depressed, the semaphore 62 is swung to a position at right angles to the side road, as explained, and when this arm 31 again rises after the vehicle travels beyond it, the semaphore remains set in the shifted position. There is a slack in the cable 63 and branches 64. When the arm 31 of the next trip device 23 is depressed it will not turn the semaphore further. When the arm 31 of the trip device 24 is depressed it turns the semaphore in a reverse direction so that it is parallel with the side road, and also takes up the slack in the cable 63 and branches 64, whereby the arm 31 of the first trip device 23 to the right, Figure 9, can again shift the semaphore to the danger position when such arm 31 is again depressed.

While I have shown only two of the trip devices 23 associated with each trip device 24, Figure 1, it is to be understood that any suitable number of trip devices 23 may be used and the trip devices 23 may be spaced for any desired distances.

It is to be understood that the forms of my invention herewith shown and described are to be taken as preferred examples of the same and that various changes in the shape, size, and arrangement of parts may be resorted to without departing from the spirit of my invention or the scope of the subjoined claims.

Having thus described my invention, what I claim is:

1. In a roadway signal apparatus, a road trip device comprising a pair of spaced generally horizontal upper arms, means to pivotally support one end of the arms, a lower arm having one end extending between the free ends of the upper arms, means for pivotally supporting the end of the lower arm remote from the free ends of the upper arms, a pin and slot connection between the free ends of the upper arms and the free end of the lower arm, and a signal device associated with and operated by the downward movement of the free end of the lower arm.

2. In a roadway signal apparatus, a pair of spaced generally horizontal upper arms, means

to pivotally support the arms near one end thereof, a lower arm, means to pivotally support one end of the lower arm and arranged near the first-named pivotal supporting means, the free end of the lower arm being arranged between the free ends of the upper arms and having an elongated slot, a pin carried by the free ends of the upper arms and operating within the slot, means to raise the lower arm, a signal device associated with the lower arm, and mechanical means operated by the lower arm to actuate the signal device.

3. In a roadway signal apparatus, a road trip device comprising a pair of spaced upper generally horizontal arms, a lower arm having a free end provided with a longitudinal slot and arranged between the free ends of the upper arms, a pin carried by the free ends of the upper arms and extending through the slot, means pivotally supporting the upper and lower arms near their opposite ends, means to raise the free ends of the arms, a gong associated with said arms, a rotary clapper for coaction with the gong, a pinion to operate the clapper, and a rack to turn the pinion and secured to one of the arms. 25

4. In a roadway signal apparatus, a road trip device comprising a pair of spaced upper generally horizontal arms, a lower arm having a free end provided with a slot and arranged between the free ends of the upper arms, a pin carried by the free ends of the upper arms and passing through the slot, a spacer arranged between the upper arms and connected therewith, means to pivotally support the opposite ends of the arms, a pulley arranged above the free end of the lower arm, a cable secured to the free end of the lower arm and passed about the pulley, a weight carried by the cable, a rack carried by the lower arm, a pinion to be engaged by the rack, a clapper operated by the pinion, and a gong to be struck by the clapper. 35

5. In a roadway signal apparatus, a trip device comprising a casing, an upper pair of spaced generally horizontal arms, a lower arm having a free end arranged between the free ends of the upper arms and extending beyond the same, a pin and slot connection between the free ends of the upper arms and the lower arm, yielding means to raise the free end of the lower arm, a rack and pinion device operated by the free end of the lower arm, an audible signal associated with said arms and mechanically operated by the rack and pinion device, means for pivotally supporting the opposite ends of the upper and lower arms, a spacer arranged between the upper arms and secured thereto, and a flexible cover extending over the casing and the upper arms. 55

6. In a roadway signal apparatus, a road trip device comprising a generally horizontal upper arm, a lower arm extending longitudinally of the upper arm and having its free end extending beyond the free end of the upper arm, means affecting a sliding connection between the free ends of the upper and lower arms, means pivotally supporting the upper and lower arms at 65 points spaced from their free ends so that such arms may swing vertically, a guide device for the free end of the lower arm to prevent lateral displacement of such arm during its vertical swinging movement, and a signal device associated with said arms and operated by the lower arm. 70

7. In a roadway signal apparatus, an upper generally horizontal arm, a lower arm extending longitudinally of the upper arm and having its 75

free end projecting beyond the free end of the upper arm, a sliding connection between the free ends of the upper and lower arms, a member having a vertical slot to receive the free end of the lower arm to form a guide for the same, means to pivotally support the upper and lower arms at points spaced from their free ends, and a signal device associated with said arms and operated by the movement of the arms.

5. 8. In a roadway signal apparatus, a generally horizontal upper arm, a lower arm extending

longitudinally of the upper arm and having its free end projecting beyond the free end of the upper arm, means connecting the free ends of the upper and lower arms, a member having a slot to receive the free end of the lower arm, 5 a signal device associated with said arms and operated by the movements of the arms, means to raise the free ends of the arms, and means to pivotally support the arms at points spaced from their free ends.
